(72) Inventors: **Richard S. Smith**, Hot Springs, AR (US); **Louis Chalfant**, Hot Springs, AR (US)

Primary Examiner — Susan Bennett Hattan

(73) Assignee: **Smith's Consumer Products, Inc**, Hot Springs, AR (US)

Assistant Examiner — Leanne Was

(**) Term: **14 Years**

(74) Attorney, Agent, or Firm — Edward D. Gilhooly

(21) Appl. No.: **29/479,308**

(57) **CLAIM**

The design for a multi-function tool, as shown and described.

(22) Filed: **Jan. 14, 2014**

DESCRIPTION

(51) LOC (10) Cl. **08-05**

FIG. 1 is a rear perspective view of the design for the multi-function tool of the invention with the knives retracted; FIG. 2 is a front elevational view of the design of FIG. 1 with the knives retracted;

(52) U.S. Cl.

FIG. 3 is a rear elevational view of the design of FIG. 1 with the knives retracted;

USPC **D8/105**

FIG. 4 is a right end elevational view of the design of FIG. 1 with the knives retracted;

(58) **Field of Classification Search**

USPC D8/1, 4, 5, 7, 9, 14, 55, 98, 99, 105; 7/118; 30/123, 155, 161, 162, 298;

81/52, 342-385, 427.5, 436, 437-439

FIG. 5 is a left end elevational view of the design of FIG. 1 with the knives retracted;

See application file for complete search history.

FIG. 6 is a top plan view of the design of FIG. 1 with the knives retracted;

(56) **References Cited**

FIG. 7 is a bottom plan view of the design of FIG. 1 with the knives retracted;

U.S. PATENT DOCUMENTS

FIG. 8 is a bottom perspective view of the design of FIG. 1 with the knives retracted;

D336,029 S * 6/1993 Ragland et al. D8/99

FIG. 9 is a top perspective view of the design of FIG. 1 with a knife extended;

D467,990 S * 12/2002 Lin et al. D22/149

FIG. 10 is a top perspective view of the design of FIG. 1 with the serrated knife extended; and,

D561,554 S * 2/2008 Taylor et al. D8/99

FIG. 11 is a bottom plan view of the design of FIG. 1 with both knives extended;

D660,126 S * 5/2012 Cagampang et al. D8/105
